[57] CLAIM

The ornamental design for a bottle, as shown and described.

DESCRIPTION

FIG. 1 is a perspective view of a bottle, showing my new design, the spray nozzle shown in phantom lines not being part of my design;

FIG. 2 is a left side elevational view thereof;

FIG. 3 is a front elevational view thereof, the rear elevational view being the mirror image thereof;

FIG. 4 is a right side elevational view thereof;

FIG. 5 is a top plan view thereof; and,

FIG. 6 is a bottom plan view thereof.

The broken lines in the drawings are for illustrative purposes only and do not form part of the claimed design.
